UNITED STATES PATENT OFFICE.

JONAS NORTHROP, OF HOPEDALE, MASSACHUSETTS, ASSIGNOR TO WILLIAM F. DRAPER, OF HOPEDALE, MASSACHUSETTS; CLARE H. DRAPER AND OLIVER H. LANE EXECUTORS OF SAID WILLIAM F. DRAPER, DECEASED.

FILLING-REPLENISHING MECHANISM FOR LOOMS.

973,127.

Specification of Letters Patent. Patented Oct. 18, 1910.

Application filed September 4, 1909. Serial No. 516,240.

To all whom it may concern:

Be it known that I, JONAS NORTHROP, a citizen of the United States, and a resident of Hopedale, in the county of Worcester 5 and State of Massachusetts, have invented an Improvement in Filling-Replenishing Mechanism for Looms, of which the following description, in connection with the accompanying drawings, is a specification, 10 like letters on the drawings representing like parts.

The invention herein to be described relates to looms, and more particularly to looms of the filling replenishing type, where- 15 in a fresh supply of filling is automatically provided when that in use fails from any cause to be laid in the shed.

As well known by those skilled in the art the filling may fail to be laid in the shed 20 for various reasons, as, for instance, when the filling carrier or shuttle becomes exhausted, or when the filling breaks. Under such conditions it is desirable that a fresh charge of filling be automatically supplied 25 to the weaving instrumentalities.

The aims and purposes of the present invention are to provide means which will be simple in construction and efficient in operation, whereby, upon failure of filling from 30 any cause, a fresh supply of filling may be delivered to the weaving elements, all as will best be made clear from the following description and accompanying drawings of one form or character of such means, it being understood that the invention is not restricted to the particular construction shown 35 and described, but in its true scope is definitely set forth by the claims.

In the drawings:—Figure 1 is a front elevation of one side portion of a loom sufficient 40 to show the features of the present invention and their relation with adjacent parts; Fig. 2 is a section on the line 2—2, Fig. 1, looking in the direction of the arrow 45 a; Fig. 3 is a section on the line 2—2, Fig. 1, looking in the direction of the arrow b; Fig. 4 is a detail sectional view on the line 4—4, Fig. 3; Fig. 5 is a detail sectional view on the line 5—5, Fig. 3, showing one form of 50 the swinging gate and its supporting and controlling elements; Fig. 6 is a section on the line 6—6, Fig. 2; and Fig. 7 is a section on the line 7—7, Fig. 2.

The loom frame 1, which may be of any

usual or desired character, is provided with 55 a suitable support for features of the replenishing mechanism, said support, in the present form of the invention, comprising a bracket 2 secured by bolts 3, 3 to the loom frame, and having rising therefrom a flange 60 or plate 4, constituting a sustaining means for the hopper 5. The hopper 5, which contains the filling carriers to be transferred to the shuttle, may be, in part at least, of the general character of that set forth in application Ser. No. 501,482, filed June 11, 1909; that is to say, it is or may be formed with its front and back walls made flaring so as to accommodate filling carriers in staggered relation, as indicated in Fig. 2, and for 70 the purpose fully announced in said prior application, a suitable slot 6 being provided for the passage of the filling ends from the carriers within the hopper to a suitable holding means for the filling ends outside the 75 same. As the filling carriers progressively move downward in the hopper they arrange themselves in single file formation, substantially as described in said prior application and as shown in Figs. 2 and 3 of the present 80 drawings, and are successively and singly given a position at the discharge throat of the hopper for transfer to the shuttle as occasion demands.

The discharge throat for the large or head 85 end of the filling carriers, which for identification may be designated the head throat, is provided with a fixed guiding back wall 7 leading downward and in such position as to guide the head end of the carrier properly 90 into the shuttle when the shuttle is positioned beneath the throat. The opposite or front wall of the head throat is formed so that when the loom is running under normal condition a filling carrier cannot pass 95 through the throat, but when a filling carrier is to be transferred to the shuttle to replace a carrier therein, the filling on which has failed from any cause, the filling carrier then in transferring position in the hopper may 100 pass through the throat, as will now be more fully explained.

Mounted on a ledge 8 secured to the bracket 2 and preferably formed as a projection on the plate 4, is a slide 9 having a flange 10 constituting the front wall of the throat 11, said slide being normally under the influence of a spring 12, one end of which

is seated against a lug 13 of the slide, and the other end of which bears against a corresponding lug 14 projecting from the plate 4, the construction being such that the spring 12 tends to move the slide to the right, Fig. 2. Obviously the slide 9 may be maintained in sliding relation to the ledge 8 by various means, but in the present form thereof the slide is provided with a side projecting portion 15 movable back and forth in a slot 16 formed in the plate 4 and held in such relation by a cotter pin 17 or otherwise, Figs. 2, 6 and 7.

Having reference to Fig. 2, it will be noted that the face of the flange 10 has a shouldered portion 18, preferably formed as shown, and that when the filling carrier is in transferring position, as indicated by the end carrier 19 of the series, the distance between this shoulder and the back wall 7 of the throat is such that the carrier 19 cannot pass therethrough, means being provided for locking the slide and consequently the front wall in this position during normal operating conditions of the loom, as will presently appear.

Suitably sustained by the bracket 2, as by means of the bearing 20, Figs. 1 and 6, and secured thereto by set screws 21, 21 is a rod 22 to the opposite end of which may be connected the outer wall of the supply hopper, as pointed out in the application mentioned.

Mounted to turn upon the rod 22 is the transferring having the hub portion 23, from which extends the actuating arm 24 having pivotally connected thereto, at 25, the dog 26, which is itself provided with the arm 27 adapted, when the dog is raised into the position indicated by full lines, Fig. 2, to be met by the bunter 28 secured to the lay, to thereby actuate the transerrer, as well understood by those skilled in the art and as indicated by dotted lines, Fig. 2.

In order that the dog 26 may be controlled in its position in accordance with the condition of filling, it is provided with a pin 29 which engages a slot 30 in a positioner 31 secured to the transverse shaft 32 as by a set screw 33, or otherwise. A spring 34 surrounding the transverse shaft 32 has one end 35 bent over and resting upon the positioner 31, the other end being secured to the loom frame at 36, the construction being such that when the loom is running with normal condition of filling, the spring 34 will hold the positioner 31 depressed with the arm 27 of the dog 26 out of the path of the bunter; but should the filling fail to be laid in the shed for any reason, the transverse shaft 32 will be moved contra-clockwise, viewing Fig. 2, by the usual and well understood filling detecting mechanism, and the positioner 31 will be raised, thus placing the arm 27 in position to be met by the

bunter 28, as indicated in Fig. 2, thus actuating the transerrer. The filling detecting mechanism may be of any usual or well known type, and, being familiar to those skilled in the art, is not herein shown, it being sufficient to note that the usual transverse shaft 32 is appropriately turned to produce the effects stated when the filling fails to be laid in the shed.

Projecting from the hub 23 is the transferring arm 37, Figs. 1, 2 and 6, the end 38 of which, Fig. 2, is disposed above the filling carrier which, for the time being, is in transferring position. Projecting laterally from the transferring arm 37 is the rod 39, Figs. 1, 2, 4 and 6, having at its end portion a filling carrier engaging member 40. The filling carrier engaging surfaces of the transferring arm 37 and the member 40 are appropriately shaped, as indicated in Figs. 2 and 4, to properly engage the filling carrier, the one adjacent the head portion of said carrier and the other remote therefrom or near the tip end of the filling carrier to properly transfer the filling carrier from its position of transfer, as indicated in Fig. 2, to the shuttle, when the latter has been positioned, as indicated by dotted lines in Fig. 2, to receive said filling carrier.

In order that the end transferring arm 37 and its connected transferring member 40 may be held in raised position, substantially as indicated in Fig. 2, there is mounted upon the rod 22 a spring 41, Figs. 1, 2 and 6, one end 42 of which engages beneath the transferring arm 37 and the other end 43 of which is held by an adjusting washer 44, Figs. 1 and 6, said adjusting washer 44 being held in adjusted position by a suitable collar 45 adjustably secured to the rod 22 by suitable means, such as the cotter pin 46 which is passed through suitable perforations in the collar 45 of said rod, the construction being such that when the parts are in normal position and the loom is working under normal conditions the spring 41 will maintain the transferring arm 37 with its end 38 and with the transferring member 40 above the filling carrier 19 which, for the time being, is in position for transfer, but when, as hereinbefore indicated, the filling fails for any reason, the positioner 31 will be raised, and as the lay beats up, the bunter 28 will actuate the transerrer to move the filling carrier, then in transferring position, into the shuttle S, the filling carrier previously therein being ejected by the incoming filling carrier. When the parts were in normal position the end 47, Fig. 2, of the slide 9 was engaged by the arm 24 of the transferring mechanism, whereby the slide, and perforce the front wall of the throat 11, was locked in position to prevent the filling carrier from moving through the throat, but upon the rearward movement of the arm 24

- due to the operation of the transferring mechanism, the slide 9 becomes released or unlocked so that the downward movement of the filling carrier 19 under the action of 5 the transferer is enabled to move the slide 9 and consequently the front wall of the throat a distance sufficient to permit the filling carrier to pass through the throat, as will be readily understood. Thus it will be 10 seen that the head throat for the passage of the filling carrier has a fixed back wall and a front wall which is fixed and immovable during the normal operation of the loom, but which is unlocked and free to be moved 15 when a filling carrier is to be transferred from the hopper to the shuttle.
- For supporting and guiding the tip portions of the filling carriers, the hopper 5 is provided with the ledge 48, Fig. 3, which ex- 20 tends in a downward direction and at its terminal portion forms the rear fixed wall 49 of the throat through which the tip end portion of the carrier passes as it is transferred to the shuttle, and which, for identi- 25 fication, may be denominated the tip throat, in contradistinction to the head throat previously herein described.
- The front wall of the tip throat is formed as a tip stop and guide surface, which is so 30 constructed that, when the loom is in normal working condition, it forms a stop to limit forward or downward movement of the filling carrier at the time being in position for transfer, and so far closes the tip 35 throat that the tip of the carrier cannot pass therethrough; but which, when a carrier is to be transferred, is moved to constitute a front guide to direct the tip of the carrier to proper position into the shuttle 40 chamber and to open the throat for the passage of the carrier tip, one form of which feature of the invention will now be described.
- Loosely mounted to turn on the rod 22 45 near the end portion thereof is an arm 50 having at its free extremity a head 51 provided with a tip engaging and guiding surface 52. At its lower portion the surface 52 is curved to form a shoulder or support 50 53 extending toward the fixed wall 49 of the tip throat, the construction being such that when the head 51 is sustained in the position indicated by full lines, Fig. 3, the tip of the filling carrier cannot pass between 55 the fixed back wall 49 and the shoulder 53, but when the arm 50 is permitted to move downward, as will presently appear, the tip of the carrier is freed to its passage through the throat.
- 60 Projecting laterally from the head 51 is a lug 54, see Figs. 4 and 6, adapted to rest on a projection 55 secured to the member 40 of the transferer, the construction being such that when the transferer is in up or 65 normal position, the projection 55 will sup- port the head 51 in the full line position, Fig. 3, but when the transferer moves downward to transfer a filling carrier to the shuttle, the arm 50 and head 51 will be permitted to fall until the foot 56 of the head 70 rests upon the top of the shuttle box, which is then beneath the throat with the shuttle in position to permit a change of filling carriers, as indicated in Fig. 3. Thus it will be apparent that while the surface 52 of the head forms a stop for the tip end of the filling carrier when in position for transfer, it likewise acts as a guide to direct the tip of the filling carrier properly into the shuttle chamber, as the carrier is being transferred. said surface at such time preferably extending to the top of the shuttle box, and the foot 56 resting thereon. Obviously the details of the tip stop and guiding head may be variously changed within the true scope 85 of the present invention, which, so far as applicant knows, is the first instance in the art where the front guide wall of the tip throat has been made to act as a stop or support for the tip of a carrier when in transferring position and a front tip guide extending to the shuttle chamber or top of the shuttle box to guide the carrier during transfer.
- As a means for limiting the extent of upward movement of the head 51, a stop 57 90 may be provided on the plate or supporting bracket 4* of the hopper; and the member 40 of the transferer may be provided with an overhang 58, Fig. 4, to confine the head 51 to proper working relation with said 95 member.
- In order to provide a rear guide for the tip of the carrier, the bracket or plate 4* has pivotally connected therewith the yielding finger 59, Figs. 3, 4, 5 and 6, the shank 60 of which passes to the outside of the bracket and is provided with a spring 61 normally acting, as in Figs. 3, 5 and 6, to hold the finger 59 in position extending across the tip 100 throat, said spring being yieldable so that 105 when the filling carrier is moved downward by the transferer, the finger 59 will turn downward to the top of the shuttle, though preferably not into the shuttle chamber, as indicated in Fig. 3, and provide a rear guide 110 for the carrier tip.
- From the construction shown and de- 115 scribed as one form of means for carrying the invention into practical effect, it will be seen that the transferer is provided with 120 portions for engaging the carrier at or adjacent the head and at or near the smaller end or tip of the carrier; and that these engaging portions have upwardly extending surfaces or faces which act as stops to the 125 downward movement of the other carriers in the hopper when the end carrier is being transferred, said surfaces or faces lifting after the transfer to permit the next filling carrier to move to transferring position. It 130

is desirable that this movement of the next filling carrier to transferring position be positive and well defined, and that not only the base or heavy portion be moved to position but the tip be also definitely located, as indicated in the drawings. To these ends the following is one form of the means embraced by this feature of the invention.

Mounted on a suitable supporting stud 62, Figs. 1, 2; 6 and 7, preferably projecting from a bracket or lug 63 sustained by the front wall of the hopper or carried by the hopper supporting bracket, is a filling carrier positioner and separator. In the present form of the invention this comprises a lever, one arm 64 of which carries a yielding finger 65 pivotally mounted on said arm 64 at 66, and normally under the influence of a spring 67 tending to straighten said finger or move it into prolongation with the arm 64, as clearly indicated in Fig. 2. Suitable stops 68 and 69 on the arm and finger respectively limit the movement of the finger in the direction stated, but permit it to move in opposition to the spring tension. The other arm 70 of said lever extends under a pin or lug 71 carried by the transferrer arm 37, and a spring 72 surrounding the stud 62 has one end 73 held by a fixed part or lug 75 and its other end engaged beneath the arm 70, said spring normally acting to turn the lever clockwise, viewing Fig. 2.

The filling carrier positioner or lever is preferably so disclosed with relation to its associated parts that the finger 65 may engage a filling carrier between the head and tip portions thereof.

From the construction described it will be apparent that upon downward movement of the transferrer arm 37 to effect filling replenishment, the pin or lug 71 will engage the arm 70 of the carrier positioner and turn it contra-clockwise, Fig. 2, the finger 65 at such time riding over the filling on the carrier above that being transferred, until on complete depression of the transferrer and consequent completion of transfer the said finger attains the position indicated by dotted lines, Fig. 2. As the transferrer rises after the transfer, the spring 72 acts upon the positioner, causing the finger 65 to engage the lowermost filling carrier in the hopper and move it into transferring position, the transferrer at such time having moved to upper or substantially normal position.

It will be noted that the filling carrier positioner not only moves the next carrier to be transferred into transferring position, but by engaging between the end portions of the carrier and between the head and tip throats it insures that both ends of the carrier will be brought into proper relation with the front walls of the throats, each of which will act as a fixed fulcrum about which the carrier will move under the force

of the positioner, should the carrier be inclined to lag at either end.

To one skilled in the art many changes may suggest themselves with respect to the details illustrated and described as one embodiment of the invention, but it is obvious the invention clearly contemplates means other than the means described for carrying it into practical effect, as applicant believes he is the first to provide a filling replenishing mechanism with a filling carrier positioner acting as stated; and also to provide among other things the throat formation of the general character described, all of which are definitely set forth in their true scope by the following claims.

What is claimed is:

1. In a filling replenishing loom, the combination of a lay, a filling carrier supply hopper, a transferrer movable with relation to the lay to transfer a carrier from said hopper to the shuttle, a filling carrier positioner disposed to engage a filling carrier, and means operative to cause the positioner to engage a filling carrier in the hopper as the transferrer transfers a carrier to the shuttle and to move said engaged carrier to transferring position as the transferrer returns to initial position after a transferring movement.

2. In a filling replenishing loom, the combination of a filling carrier supply hopper, a transferrer to transfer a carrier from said hopper to the shuttle, a filling carrier positioner disposed to engage a filling carrier between its ends while in the hopper and move it to transferring position, and means under control of the transferrer to operate said positioner.

3. In a filling replenishing loom, the combination of a filling carrier supplying means, a transferrer arm having portions to engage and move a carrier from said supplying means, a filling carrier positioner to engage a carrier between its ends and move it to transferring position in said supplying means, and operating means for said positioner acting as the transferrer returns to initial position following a transfer to move a filling carrier to transferring position.

4. In a filling replenishing loom, the combination of a filling carrier supplying means, a transferrer to move a carrier from said supplying means, a filling carrier positioner to engage a carrier between its ends and move it to transferring position in said supplying means, and operating means for said positioner controlled by the transferrer.

5. In a filling replenishing loom, the combination of filling carrier supplying means, a transferrer for transferring a filling carrier from said means to the shuttle, a filling carrier positioner normally engaging a rear portion of a filling carrier when in transferring position, and means acting to cause

the positioner to move over and engage a rear portion of another carrier and move it to transferring position following a transferring movement of the transferrer.

5 6. In a filling replenishing loom, the combination of filling carrier supplying means, a transferrer to remove a carrier from said means, a filling carrier positioner, and means to cause said positioner to engage a carrier 70 in the supplying means as the transferrer removes a carrier and to position the engaged carrier for transfer as the transferrer returns to initial position.

15 7. In a filling replenishing loom, the combination of filling carrier supplying means, a transferrer to remove a carrier from said means, a filling carrier positioner, and means to cause said positioner to engage a carrier 75 between its ends in the supplying means as the transferrer removes a carrier and to position the engaged carrier for transfer as the transferrer returns to initial position.

20 8. In a filling replenishing loom, the combination of filling carrier supplying means, a transferrer to remove a carrier from said means, a filling carrier positioner, and means to cause said positioner to engage above the 80 filling carrier next to be moved to transferring position, as the transferrer transfers a carrier, and to move said engaged carrier into transferring position when the transferrer is moved to initial position.

25 9. In a filling replenishing loom, the combination of filling carrier supplying means, a transferrer to remove a carrier from said means, a filling carrier positioner, and means under control of the transferrer to cause 85 said positioner to engage above the filling carrier next to be moved to transferring position, as the transferrer transfers a carrier, and to move said engaged carrier into transferring position when the transferrer is moved to initial position.

30 10. In a filling replenishing loom, a filling carrier supply, a transferrer having a plural number of filling carrier engaging portions, a filling carrier positioner disposed to engage a filling carrier in the carrier supply at 90 a point between two of said engaging portions, and means for causing the positioner to move a filling carrier to transferring position following a transferring movement of the transferrer and to maintain said carrier in transferring position.

35 11. In a filling replenishing loom, a filling carrier supply, a transferrer, means to operate the transferrer to cause it to push a carrier into the shuttle, a filling carrier positioner having a yielding portion, and means 95 to cause said yielding portion to engage above a carrier next to be positioned for transfer and move it to transferring position following a transferring movement of the transferrer.

40 12. In a filling replenishing loom, the com-

bination of a lay, a hopper for containing a supply of filling carrier, a transferrer to transfer a carrier from the hopper to the shuttle, a filling carrier positioner normally in engagement with the filling carrier that 70 is in transferring position and acting to maintain said filling carrier in said position until the action of the transferrer, and means operating to then move the transferrer to a rear portion of the carrier next to 75 be placed in transferring position and move said carrier to and hold it in transferring position.

13. In a filling replenishing loom, the combination of the lay, a filling carrier supplying means having a head and tip throat for the passage of a filling carrier, a transferrer to move a filling carrier through said throats, a filling carrier positioner normally acting upon the filling carrier in transferring position and maintaining said carrier with its head and tip positioned at the throat passages, and means acting upon transfer of said carrier to move the positioner over the next filling carrier and to then move it to 90 hold it in the throat passages in position for transfer.

14. In a filling replenishing loom, the combination of filling carrier supplying means, a transferrer to transfer a carrier from said 95 means to the shuttle, and a filling carrier positioner to engage the filling carrier next to be placed in transferring position and to move said engaged carrier to and maintain it in transferring position in the supplying 100 means after the transferrer has operated and transferred a filling carrier to the shuttle.

15. In a filling replenishing loom, the combination of filling supplying means having head and tip throats for the passage of a 105 filling carrier, a transferrer and its operating means, a filling carrier positioner to engage a filling carrier in the supplying means between said head and tip throats, and means operative upon movement of the 110 transferrer for actuating said positioner to move a carrier to transferring position.

16. In a filling replenishing loom, the combination of filling supplying means having head and tip throats for the passage of a filling carrier, a transferrer and its operating 115 means, a filling carrier positioner to engage a filling carrier between said head and tip throats and means controlled by the transferrer for actuating said positioner to move 120 a carrier to transferring position.

17. In a filling replenishing loom, the combination of filling supplying means having head and tip throats provided with yielding 125 front walls for the passage of a filling carrier, a transferrer and its operating means, a filling carrier positioner to engage a filling carrier between said head and tip throats, means for actuating said positioner to move a carrier to transferring position, and means 130

for rendering the front walls of said throats unyielding as the positioner acts to position a carrier.

18. In a filling replenishing loom, the combination of filling carrier supplying means having head and tip throats provided with movable front walls, a transferrer, a filling carrier positioner to engage a carrier between its ends and move it to transferring position, and means to prevent the front walls of the throats from yielding as the carrier is positioned.

19. In a filling replenishing loom, a transferrer, filling carrier supplying means having a throat for the passage of a carrier, means for causing the transferrer to move a carrier through said throat, the front wall of said throat being movable, and means for locking the said wall against movement when the transferrer is in normal position and to unlock and free it to movement when the transferrer is operated.

20. In a filling replenishing loom, the combination of a transferrer, filling carrier supplying means having a throat for the passage of filling carriers moved by said transferrer, a fixed back wall and a movable front wall for said throat, and means to lock and unlock the front wall.

21. In a filling replenishing loom, the combination of a hopper for containing a supply of filling carriers, said hopper having a throat for the passage of said carriers, one of the walls of said throat being fixed and the other movable, means for locking and unlocking the movable wall, and a transferrer to move a carrier through the throat when the movable wall is unlocked.

22. In a filling replenishing loom, the combination of filling carrier supplying means having a throat for the passage of filling carriers, one of the walls of said throat being fixed and the other being movable, a shoulder on one of said walls to prevent passage of the filling carriers through the throat, means for locking and unlocking the movable wall of the throat, and a transferrer to move a carrier through the throat when the movable wall is unlocked.

23. In a filling replenishing loom, the combination of filling carrier supplying means having a throat for the passage of filling carriers provided with a fixed wall and a slideable wall, means for locking and unlocking the slideable wall, and a transferrer to move a carrier through the throat when the movable wall is unlocked.

24. In a filling replenishing loom, the combination of filling carrier supplying means having a throat for the passage of filling carriers provided with a fixed wall and a slideable wall, yielding means acting on the slideable wall to normally close the throat to the passage of filling carriers, one of said walls being provided with a shoulder,

and means for locking and unlocking the slideable wall.

25. In a filling replenishing loom, the combination of a hopper having a throat provided with a fixed and a movable wall, a transferrer, and means operating when the transferrer is in initial position to lock the movable wall and when the transferrer is moved to transfer a carrier to unlock said movable wall.

26. In a filling replenishing loom, the combination of a transferrer, filling supplying means having head and tip throats for the passage of a filling carrier, one wall of each of said throats being movable to permit the carrier to pass, and means for holding the movable wall of each throat from movement when the transferrer is in initial position.

27. In a filling replenishing loom, the combination of a transferrer, filling supplying means having head and tip throats for the passage of a filling carrier, one wall of each of said throats being movable to permit the carrier to pass, and means for holding the movable wall of each throat from movement when the transferrer is in initial position, and permitting the movable walls to move and open the throats to the passage of the carrier when the transferrer is operated.

28. In a filling replenishing loom, a hopper for containing a supply of filling carriers, a transferrer, and a carrier tip guide controlled by the transferrer and adapted to move into contact with the top of the shuttle box and rest thereon during the action of the transferrer to guide the tip of the carrier into the shuttle.

29. In a filling replenishing loom, the combination of a hopper provided with a throat for the passage of the carriers, one wall of said throat being fixed and the other movable, a transferrer, and means between the transferrer and movable wall of the throat to permit the latter to move downward and rest upon the top of the shuttle box as the transferrer moves a carrier into the shuttle.

30. In a filling replenishing loom, the combination of a hopper having a tip throat for the passage of filling carriers, front and back guiding means for the tip of the carrier extending to the top of the shuttle as the carrier passes into the shuttle, and a transferrer.

31. In a filling replenishing loom, the combination of a transferrer, a hopper having a throat for the passage of a filling carrier, said throat having a fixed and a movable wall, said movable wall being movable as the transferrer transfers a carrier and forming a guide for the carrier to the top of the shuttle, and a yielding finger normally extending across the throat and forming, as

the carrier moves into the shuttle, a guide for the carrier opposite the movable wall.

32. In a filling replenishing loom, the combination of a shuttle box, filling carrier supplying means having a throat for the passage of filling carriers as they are transferred to the shuttle, a transerrer to move the carriers through said throat, and a tip guide in front of the carrier tip having a 10 guiding surface forming the front wall of the throat and extending to the top of the shuttle box to guide the tip into the shuttle as the carrier is transferred.

33. In a filling replenishing loom, the combination of a shuttle box, filling carrier supplying means, a transerrer to transfer filling carriers to the shuttle, and a tip guide disposed in front of the tip of the filling carrier and having a tip guiding surface 20 tending to the top of the shuttle box in a plane parallel to the plane of movement of the carrier tip to guide the tip of the carrier as it is transferred.

34. In a filling replenishing loom, the combination of a lay, a shuttle box, a filling carrier supplying means, a transerrer to transfer filling carriers from said supplying means, a tip guide having a guiding surface disposed in front of the tip of a filling carrier when in transferring position, said surface extending to the top of the shuttle box as the carrier is being transferred, and means to actuate the transerrer and cause the tip of the carrier to move along said 35 guiding surface from the supplying means to the top of the shuttle.

35. In a filling replenishing loom, the combination of a shuttle box, filling carrier supplying means, a tip guide disposed opposite the tip of a carrier when in transferring position and having a shoulder to hold the tip of the carrier and a guiding surface extending upward from said shoulder, a transerrer, and means to cause the 45 tip guide guiding surface to extend to the top of the shuttle box and guide the tip of the carrier as the latter is being transferred.

36. In a filling replenishing loom, the combination of a shuttle box, filling carrier 50 supplying means having a tip throat for the passage of the tip of a filling carrier, the front wall of said throat being movable and having an extended guiding surface, a transerrer, and means to permit the front wall 55 of the throat to move downward toward the top of the shuttle box and form a continu-

ous guiding surface from the supplying means to the top of the shuttle box to guide a filling carrier as it is transferred to the shuttle.

37. In a filling replenishing loom, the combination of filling supplying means having head and tip throats for the passage of filling carriers, a transerrer to move filling carriers through said throats, the front walls 65 of each of said throats being movable, and means for causing said front walls to close and lock the throats to the passage of filling carriers when the transerrer is not to transfer a carrier to the shuttle and permit said 70 front walls to move and open the throats to the passage of a filling carrier when a transfer is to be made.

38. In a filling replenishing loom, the combination of filling carrier supplying 75 means, a transerrer, means to cause the transerrer to push a filling carrier from the supplying means to the shuttle, and a filling carrier positioner controlled by the trans- 80 ferrer to move a filling carrier into transferring position.

39. In a filling replenishing loom, the combination of the lay, a hopper for containing filling carriers, a transerrer for transferring a filling carrier from the hopper to the shuttle, a filling carrier positioner comprising an arm having a yielding end portion, means for causing said yielding end portion to normally hold a filling carrier in transferring position, and means operating as the transerrer transfers a carrier to move the yielding end portion of the positioner back of the next filling carrier in the hopper and to then move said carrier to transferring position as the transerrer re- 90 turns to initial position.

40. In a filling replenishing loom, the combination of a lay, a hopper for containing filling carriers, a transerrer for transferring a filling carrier from the hopper to 100 the shuttle, a filling carrier positioner, a spring acting to hold said positioner against a carrier in transferring position, and operating means for the positioner controlled by movement of the transerrer.

In testimony whereof, I have signed my name to this specification, in the presence of two subscribing witnesses.

JONAS NORTHRUP.
